UNITED STATES PATENT OFFICE.

JOHN WALDHEIM, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed June 14, 1923. Serial No. 645,261.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

The invention relates to a machine for 10 typing upon work-webs, comprising several plies, either fan-folded or unattached to each other, and upon each of which plies are usually printed a succession of forms; the form lengths or sections of one ply registering with those of the other plies, and carbons being interleaved with the plies. 15 The work-webs may be continuous, or of indefinite length, according to the number of forms which compose the same. Ordinarily, however, or at least until so worn 20 as to call for replacement, a fixed length of carbon-sheet is employed; the carbons being shifted, relatively to the work-webs from one form-length to the next succeeding 25 form-length of work-webs when the typing of a form is completed. The usual practice has been; after typing of a form, first, to lift the platen bodily to release the web therefrom and to release the carbons for 30 their shift; then to shift, one form-length rearward, a carbon-carrier with the carbons attached thereto, while holding the work-webs; and then to reset the composite web for commencement of typing on the next 35 form and to replace the platen.

For the purpose, among others, of avoiding the necessity of lifting the platen preliminary to shift of the carbons, it has been proposed; to utilize the backward throw of 40 the carbon-carrier, not to effect the form-to-form shift of the carbons relatively to the work-webs, but to draw back the entire composite web sufficiently to release the carbons from the platen; and then, while holding 45 the carbon-carrier, with the carbons, stationary in rearward position, to utilize the platen, by forward rotary movement of the same, to advance the work-webs a form-length over the carbons. This being done, 50 the carbon-carrier may be released to permit a further forward rotary movement of the platen to advance the entire composite

web to position for commencement of typing on the new form.

An object of the present invention is the provision of means for effecting this last-mentioned forward throw of the platen, and for automatically determining the extent of same; thus precluding inaccuracies on the part of the operator; and, by relieving the operator of the necessity of care and attention, expediting the operation.

Composite webs, of the character described, have also been used in typewriting machines having computing attachments. It commonly happens, however, in such machines, that a part of the computing mechanism is found on the back of the machine in such position as to require a special table structure or support for the carbon-carrier, to clear these computing parts and to permit of movement and adjustment of the same.

A feature of the present invention is a carbon-carrier table made substantially straight to provide for free movement of the carbons and work-webs thereover, and also being of an incline, to constitute in effect a straight-line continuation of the rear paper-table on the platen-carriage; so as to provide a straight path for the web to the platen; thereby eliminating such bending of the web over the upper edge of the paper-table at the rear of the platen as would interfere with easy relative shift of the carbons and work-webs.

A further object of the invention is the provision of novel means, for effecting the rearward throw of the carbon-carrier, conveniently operable from the front of the carbon-carrier table, and permitting of such control of the carbon-carrier as to preclude slip of the same down the table.

Other features and advantages will hereinafter appear.

In the accompanying drawings,

Figure 1 is a view in side elevation, partly cross-sectional, of the platen-carriage, computing mechanism and certain other parts of the machine equipped with the carbon-carrier table and other devices of the present invention.

Figure 2 is a view, in front elevation, of the mechanism shown in Figure 1.

Figure 3 is a view, in side elevation, of the device for effecting a predetermined forward throw of the platen.

Figure 4 is a top plan view of the forward 5 part of the carbon-carrier table frame.

Figure 5 is a view, in side elevation, of the carbon-carrier table and device for controlling the movements of the carbon-carrier; the composite web being shown in position 10 for commencement of typing of a form.

Figure 6 is a view, in side elevation, showing the positions of the leading ends of the work-webs and carbons after shift of the work-webs with respect to the carbons.

15 Figure 7 is a view, in side elevation, showing the position to which the composite web is drawn at the commencement of writing on the form.

Upon depression of the keys (not shown) 20 of a typewriter forming part of a book-keeping machine of the Underwood-Hanson type, type-bars 11 are swung upwardly and rearwardly to cause types 12 thereon to engage a cylindrical platen 13, mounted on an 25 axle 14 journaled in a carriage 15, which is supported for sliding movement transversely of the typewriter by means including a rear rail 16 fixed on the typewriter-frame 17. Each type-bar in its effective movement 30 actuates the usual escapement mechanism (not shown) and effects a letter-feeding movement of the carriage.

As is usual in bookkeeping machines of the type referred to, the frame 17 of the 35 typewriter is set on the casing 18 of the computing mechanism, and provision is made of means whereby the letter-feeding movement of the carriage will effect denomination-selecting for the computing mechanism. To this end, provision is made of brackets 19 extending rearwardly from the typewriter-carriage and of rods 20 and 21 carried thereby. Rotatably and slidably mounted on the rod 20 is a denomination-40 selector 22, which may be held in proper letter-space positions therealong by means of a tooth 23 engaging notches in the rod 21, the selector 22 normally lying in depressed or ineffective position. Obviously, 45 a plurality of selectors may be used.

Upon a letter-feeding movement of the carriage into a computing zone determined by one of the selectors, a frusto-conical roller 24 on the rear end of the selector 22 will 50 ride up on the conical end of a roller 25, having a cylindrical portion of substantially the length of the computing zone, and cause a tappet 26 on the selector to engage seriatim the forward ends of jacks 27 of a certain 55 set, to advance seriatim the usual pin-bars by connections (not shown). Provision is made of the usual jack-housing 28 and the usual housing 29 for the thrust-rods (not shown), by which the movements of the 60 jacks 27 are transmitted to the computing

mechanism, the housing 29 being connected to the jack-housing 28 at its forward end by any suitable means, and the jacks and jack-housing being supported on the typewriter-frame by any suitable means, such as 70 a bar 29^a and brackets 29^b. There may be several sets of jacks, and actuation of a set of jacks by one selector 22 and not by others may be obtained by arranging the different sets with the forward ends of the jacks 75 extending to different positions toward the front of the machine, and by arranging the tappets 26 on the different selectors 22 in accordance with the sets of jacks to be actuated thereby. The brackets 19 may also be 80 utilized to support a toothed bar 31, on which may be positioned, at letter-space intervals, tabulator-stops 32 in position to be engaged by counter-stops (not shown), when the latter are lifted by means (not shown). The computing mechanism and the denomination-selecting mechanism, forming part thereof, may be, in general, similar to that disclosed in the patent to Richard M. Becker, No. 1,296,355, granted March 4, 90 1919.

A carbon-carrier table 35 extends upward and rearward from the platen-carriage 15, and is secured to the latter to move therewith in letter feed and return directions in 95 the following manner. The end pieces 36^a of the carriage-frame are connected by a cross tie or bar 37; and on the end plates 36 of the case-shift frame are supported the usual rear paper-table and apron 38. Also secured to the bar 37, by means of screws 39, are a pair of brackets 40, the upper ends of these brackets having ears 41. Rods 42, which form the side reaches of the carbon-carrier table, have lateral offsets 43 which 100 abut the bracket ears 41 and which are secured to the bracket ears by screws 44, which thread through the ears and into the ends of the offsets 43. Sufficiently above the offsets 43, to clear the computing mechanism hereinafter described, is a cross rod or bar 45 which forms the front reach of the carbon-carrier table and which connects the side reaches 42 thereof. The side reaches 42 of the carbon-carrier table are 105 connected at the rear by a similar cross bar or tie 46. Brackets, comprising forward arms 47 and rearward arms 48, support the carbon-carrier table rearward of the platen-carriage; the arms 47 and 48 of each of such side brackets having offset ears 49 and 50, respectively, secured by screws 51 to the under side of the corresponding table side rod 42. The arms 47 and 48 of each 110 of these brackets converge to an arm 52 carrying an ear 53 offset laterally therefrom. The ears 53 have fast thereto a bar 54 which serves to tie these brackets together and on which are journaled a pair of rollers 55 by means of which the brackets 47-48, and 115 120 125 130

consequently the carbon-carrier table, are supported for movement in letter feed and return directions, with the platen-carriage, on a rail 56 carried by a pair of standards 57. Guards 58 also attached to the cross tie 54 pass down and around the rail 56 to hold the carbon-carrier table to its seat on the standards 57. The standards 57, one at each side of the machine, are secured by screws 59 to a table 60. The table 60 supports the frame 18 of the computing machine; and on this frame 18 is supported the main frame 17 of the typewriting machine. The carbon-carrier table is, therefore, supported both fore and aft for movement with the platen-carriage transversely of the table 60 and the machine frame 17.

The work-web, shown in three plies 62, is led into the machine upward from the rear thereof over a guide-plate 63 secured to the rear cross-piece of the carbon-carrier table, and thence downward and forward in the direction of the platen. At or just in front of the guide-plate 63 are side gages 64 for the work-web. These gages are adjustably set (according to the width of the web) on a rod 65 supported by arms 66 on the rear cross-piece 46 of the carbon-carrier table. From the rod 65 the plies of the work-web are led through the carbon-carrier 67, where they become interleaved with the carbons 68, and are thence led downward and forward over the carbon-carrier table; and over the rear paper-table and apron 38 down behind and around to the front of the platen. Above the printing line of the platen, the work-webs pass between the platen and a knife 69 carried by the side pieces of the platen-frame. Above the knife 69, the side pieces of the platen-frame are connected by a cross-plate 70, to which is secured a staff 71 having a gage 72 adjustably secured thereto. As indicated in Figure 6, the purpose of this gage is to position the leading ends of the work-webs at certain times in the operation of the machine.

The carbon-carrier carriage consists of a base-plate 73 having on the under face thereof, two at each side, rollers 74 grooved, to receive, and ride upon, rails 75, one at each side of the carbon-carrier table; the rails 75 being secured to and extending longitudinally of the side reaches 42 of the carbon-carrier table on the upper side of the latter. On the carbon-carrier base-plate 73, one at each side thereof, is a standard 76; the standards 76 being stepped, as shown in Figures 1 and 2. Secured to the steps of these standards are blades 77 to which are attached the rear ends of the carbon-sheets 68. As shown in Figure 1, the work-webs are spread at the carbon-carrier by the blades 77 so as to be freely interleaved with the carbon-sheets.

It will be understood that when the composite web, consisting of work-sheets and interleaved carbon-sheets, is in such position that the carbons are held to the platen by the usual front and rear feed-rolls 78, the line-feed movement of the platen, in the typing of a form, results in a downward and forward feed of the composite web, such that the carbon-carrier is correspondingly fed downward and forward on its rails 75 on the carbon-carrier table. This movement of the carbons with the carbon-carrier and with the work-webs proceeds until the writing of a form is complete.

On completion of a form, it becomes necessary to shift the carbons rearward relatively to the work-webs to withdraw the carbons from the typed form and interleave the same with the succeeding untyped form. For this purpose, the feed-rolls 78 are first thrown off the platen to release the carbons to rearward movement. The mechanism for throwing off the feed-rolls may be that found in the Underwood standard typewriting machine, and consisting of a finger-piece 79 connected with a link 80 for turning a shaft 81 having flats for spreading apart arms 82, which carry the feed-rolls and which are pivoted on another shaft 83; the shafts 81 and 83 being mounted in the side plates of the platen-frame. When the feed-rolls are thrown off, the carbon-carrier 67 may be moved backward from Figure 5 to Figure 1 position without tearing the carbons. In the Figure 1 position, it will be noted that the carbons 68 have been drawn back to position to clear the same from the platen. The backward movement of the carbon-carrier from Figure 5 to Figure 1 position is effected by the following means.

The upper and lower, or rear and front edges, of the base-plate 73 of the carbon-carrier are connected by loops 84 and 85, respectively, to a belt 86, which is thereby made endless, and which passes over a pulley 87 at the upper rear end of the carbon-carrier table and a pulley 88 at the lower forward end of the carbon-carrier table. Both pulleys 87 and 88 are shown as having teeth 89 to engage in holes 90 in the belt 86. The upper pulley 87 is an idler on a stub-shaft 91 journaled in a bracket 92 secured by screws 93 to the under side of the carrier table rear rail 46. Pulley 88 is fast to a shaft 94 journaled at one end in a bracket 95 at the left-hand side of the carbon-carrier table and at its other end to a bracket 96 at the right-hand side of the carbon-carrier table. The bracket 96 is an L-shaped plate secured by screws 97 on the upper side of the L-shaped portion 42-43 of the side piece of the carbon-carrier table; and having an offset and downwardly depending ear 98 in which the end of the shaft 94 is set. A collar 99 secured to the

shaft 94 holds the latter against rightward displacement on the bracket ear 98. The left-hand bracket 95 comprises a plate 100 set at some distance to the left of the left-hand table reach 42 and having an ear 101 offset therefrom and secured to the under side of the left-hand table bar 42. At its forward end the bracket-plate 100 has an offset 102 which is secured by screws 103 to the upper side of the L-shaped portion 42-43 of the left-hand table bar 42.

On a hub 104 secured by a set-screw 105 to the shaft 94 at the right-hand side of the bracket-plate 100 is a pinion 106 meshing with a pinion 107 secured by a set-screw 108 to a stub-shaft 109 also journaled in the bracket-plate 100 at the right-hand side thereof. Fast to the stub-shaft 109 at the left-hand side of the bracket-plate 100 is another pinion 110 in mesh with an arcuate rack 111 secured by screws 112 to a handle 113; the latter being pivoted at 114 to the bracket side plate 100. In order that the handle-arm 113 may be swung without striking the pinion 110, the rack is offset leftward at 115 where it connects with the handle 113.

From the above connections, it will be seen that, if the handle 113 is swung from Figure 5 to Figure 1 position, the rack 111 will rotate the pinions 110 and 107 clockwise (Figure 5) to cause the pinion 106 to turn counterclockwise (Figure 5), and thereby, through the pulley 88, to drive the belt in such direction as to move the carbon-carrier upward and rearward on the carbon-carrier table. A stop 116 on one of the side reaches 42 of the table, by engagement of the upper edge of the base-plate 40 73 of the carbon-carrier, may determine the upper or Figure 1 position of the latter, and consequently the throw of the latter necessary to clear the leading edges of the carbons from the platen. Tendency of the 45 carbon-carrier to slide down the table may be resisted by a coil spring 117 on the shaft 94; one end of the coil spring being connected to the pulley 88 and the other end to the bracket 98. The carbon-carrier will, 50 of course, be held in Figure 1 position so long as the handle 113 is held by the operator in its Figure 1 position.

When the composite web is in position, with the carbons free of the platen, a shift 55 of the work-webs with respect to the carbons may be effected. To this end, the pressure rolls are re-applied to the platen, and, with the carbon-carrier held in its Figure 1 position, whether by the spring 117, or 60 more assuredly by the handle 113, the platen is rotated forward to bring the leading ends of the work-webs to the gage 72. The position of this gage determines a forward 65 movement of the work-webs, equal to one form length, with respect to the car-

bons. The forms may be of different lengths on different webs, and hence the adjustability of the gage 72. The rotary movement of the platen to bring the leading ends of the work-webs to the gage 72 70 may be effected by the usual finger-knobs 118 on the platen-shaft, or by a ratchet-wheel 119 forming part of the line-spacing mechanism.

It now remains to set the composite web 75 to position for commencement of typing on a fresh form. Such a positioning of the composite web must ordinarily be a definite movement, and must certainly be a movement sufficient to bring the leading edges 80 of the carbons to the printing lines, from Figure 6 to Figure 7 position. In Figure 7 position of the composite web, a previously-typed form may be detached by drawing the work-webs against the knife 85 blade 69.

As hereinbefore stated, the present invention embraces means for determining automatically the precise movement of the platen required to feed the web from Figure 6 to Figure 7 position, to set the same in proper position for commencement of typing, and to position the previously-typed form correctly for removal of the same by 90 means of the knife 69, as shown in Figure 95 7. This means (see Figures 3 and 2) comprises a pinion 120 loose on the platen-axle 14, and a ratchet-wheel 121 made fast to the platen-axle by means of a key 122. Also supported by, but disconnected from, the platen-axle is a plate or bracket 123. An arm 124 secured at 125 to the plate 123 and at 126 to the right-hand side plate 36 of the platen-frame holds the plate 123 100 against angular displacement. Pivoted at 127 on the plate 123 is an arm or handle 128 which carries a rack 129 in mesh with the pinion 120. Fast to the pinion 120 is an arm 130, on the end of which is pivoted 110 a pawl 131 for engagement with the teeth of the ratchet-wheel 121. A spring 132 tends to throw the pawl into engagement with the ratchet-wheel. A stop-pin 133 on the plate 123, however, in the Figure 3 position of the parts, by engagement with a tail piece 134 on the pawl, disengages the pawl from the ratchet-wheel and holds the same free therefrom against the action of the spring 132; this being the normal or idle position of the parts. To turn the platen, to feed the web from Figure 6 to Figure 7 position, the arm 128 is pulled forward from its full-line Figure 3 to its dotted-line Figure 3 position. This movement of the arm causes the rack 129 to rotate the pinion 120 in clockwise (Figure 3) direction with the arm 130 and pawl 131. As soon as the pawl leaves the pin 133 it engages the ratchet-wheel 121, and, the latter being secured 115 to the platen-axle, carries with it the platen. 120

This forward rotary movement of the platen continues until the pawl strikes another stop-pin 135 on the plate 123; whereupon movement of the parts is arrested with the 5 handle in Figure 3 dotted-line position and the web in Figure 7 position. At the time the handle 128 is thrown forward the handle 113 stands released, and the carbon-carrier 67 moves down the table a distance commensurate with the advance of the carbons from Figure 6 to Figure 7 position. Thereafter, in the line-spacing operation in the 10 typing of the form, the carbon-carrier continues to move down the table until typing 15 on the form is completed. The arm 128 may be automatically returned to normal (Figure 3) position by a spring 136.

It will be noted that the position, length, and shape of the brackets 40 is such as to 20 clear the denominational selector 22 and the jack-housing 28 and to support the carbon-carrier table clear of the denominational selector and jack-housing. It will also be noted that the position of the first cross-bar 45 of the carbon-carrier table is such 25 as to permit upward swing of the selectors for adjustment thereof.

It will be seen from Figures 1 and 5 that the incline of the carbon-carrier table is 30 such as to make it practically a straight-line continuation of the rear paper-table on the platen-carriage; so that, without bending, the web passes from the top of the carbon-carrier table to its point of engagement with the platen.

Variations may be resorted to within the 35 scope of the invention, and portions of the improvements may be used without others. Having thus described my invention, I 40 claim:

1. In a typewriting machine, a rotatable platen, means for holding work-webs, having carbons interleaved therewith, for line-space feed with the platen, a table over 45 which the composite web is fed toward the platen, a carbon-carrier on the table, to which the carbons are connected at their rear, a belt connected to the carbon-carrier, 50 pulleys for the belt at the front and rear of the table, a shaft to which one of the pulleys is fast, a counter-shaft, step-up gearing connecting the shafts, and means for turning the gears to cause the belt to shift the carbon-carrier.

2. In a typewriting machine, a revolute platen, means for holding work-webs, having carbons interleaved therewith, for line-space feed with the platen, a table over 60 which the composite web is fed toward the platen, a carbon-carrier on the table, to which the carbons are connected at their rear, a belt connected to the carbon-carrier, 65 pulleys for the belt at the front and rear of the table, a shaft to which one of the pulleys is fast, a gear on the pulley-shaft,

a pivoted arm or handle, and an arcuate rack on the arm for driving the gear to cause the belt to shift the carbon-carrier.

3. In a typewriting machine, a rotatable platen, means for holding work-webs, having carbons interleaved therewith, for line-space feed with the platen, a table projecting from the rear of the platen and over which the composite web is fed toward the platen, a carbon-carrier on the table, to 70 which the carbons are connected at their rear, means for moving the carbon-carrier backward to clear the carbons from the platen after typing of a form, the table being inclined upward throughout the path 75 of movement of the carbon-carrier thereon, and spring-controlled means for holding the carbon-carrier against downward slip after the carbons have been cleared from the platen.

4. In a typewriting machine, a rotatable platen, means for holding work-webs, having carbons interleaved therewith, for line-space feed with the platen, computing mechanism on the back of the machine, brackets 90 on the machine extended over the computing mechanism, a table, supported on the brackets, projecting upward toward the rear and over which the composite web is fed toward the platen, a carbon-carrier on the table, 95 to which the carbons are connected at their rear, and gearing on the table above the computing mechanism, for moving the carbon-carrier backward to clear the carbons from the platen after typing.

5. In a typewriting machine, a rotatable platen, means for holding, to the platen, work-webs, having carbons interleaved therewith, for line-space feed with the platen, a table over which the composite web is fed 100 toward the platen, a carbon-carrier on the table, to which the carbons are connected at their rear, gear actuated driving means for effecting a backward movement of the carbon-carrier to clear the carbons from the 110 platen after typing of a division thereof, means connected with said gear actuated driving means for holding the carbon-carrier thus retracted, and means co-operating 115 with the platen whereby, upon forward rotation of the platen while the carbon-carrier is held retracted, to effect forward feed of the work-webs for a relative division-to-division backward shift of the carbons along the work-webs.

6. In a typewriting machine, a rotatable platen, means for holding, to the platen, work-webs, having carbons interleaved therewith, for line-space feed with the platen, a table over which the composite web 125 is fed toward the platen, a carbon-carrier on the table, to which the carbons are connected at their rear, means for effecting a backward movement of the carbon-carrier to clear the carbons from the platen after typing,

means for holding the carbon-carrier thus retracted, means co-operating with the platen whereby, upon forward rotation of the platen while the carbon-carrier is held retracted, to effect forward feed of the work-webs for a relative step-by-step backward shift of the carbons along the work-webs, and means for automatically determining a further forward rotation of the platen, upon 5 release of the carbon-carrier, to position the composite web for commencement of typing.

7. In a typewriting machine, a rotatable platen, means for holding, to the platen, work-webs, having carbons interleaved therewith, for line-space feed with the platen, a table over which the composite web is fed toward the platen, a carbon-carrier on the table, to which the carbons are connected 10 at their rear, means for effecting a backward movement of the carbon-carrier to clear the carbon from the platen after typing, means for holding the carbon-carrier thus retracted, means co-operating with the platen 15 whereby, upon forward rotation of the platen while the carbon-carrier is held retracted, to effect forward feed of the work-webs for a relative step-by-step backward shift of the carbons along the work-webs, an arm 20 connected to the platen to rotate the latter forward, and a stop for determining the proper throw of the arm and forward rotation of the platen to position the composite web for commencement of typing.

35 8. In a typewriting machine, a rotatable platen, means for holding, to the platen, work-webs, having carbons interleaved therewith, for line-space feed with the platen, a table over which the composite web is 30 fed toward the platen, a carbon-carrier on the table, to which the carbons are connected at their rear, means for effecting a backward movement of the carbon-carrier to clear the carbons from the platen after typing, means for holding the carbon-carrier thus retracted, means co-operating with the platen whereby, upon forward rotation of the platen while the carbon-carrier is held retracted, to effect forward feed of the work-webs 40 for a relative step-by-step backward shift of the carbons along the work-webs, an arm connected to the platen to rotate the latter forward, and a stop for determining the proper throw of the arm and forward rotation of the platen to position the composite web for commencement of typing; the connection of the arm to the platen comprising a ratchet-wheel fast to the platen-shaft, a pinion loose upon the shaft, a pawl 45 carried by the pinion, for one-way engagement with the teeth of the ratchet-wheel, and a gear from the pinion to the arm.

9. In a typewriting machine, a rotatable platen, a platen-shaft, a frame in which the 50 platen-shaft is journaled, and means for ro-

tating the platen, comprising a ratchet-wheel fast to the platen-shaft, a pinion loose upon the shaft, a pawl carried by the pinion, for one-way engagement with the teeth of the ratchet-wheel, an arm pivoted on the 70 frame independently of the platen, and a rack on the arm in mesh with the pinion.

10. In a typewriting machine, a rotatable platen, a platen-shaft, a frame in which the platen is journaled, a bracket supported by 75 the platen-shaft, but disconnected therefrom so that the platen may turn without moving the bracket, means connecting the bracket to the platen-frame to hold the bracket against displacement, an arm pivoted to the bracket, 80 and gears connecting the arm to the platen for rotation of the platen by movement of the arm.

11. In a typewriting machine, a rotatable platen, means for holding work-webs, having 85 carbons interleaved therewith, for line-space feed with the platen, a table over which the composite web is fed toward the platen, a carbon-carrier on the table, to which the carbons are connected at their 90 rear, a handle pivoted on the table, and gearing connecting the handle to the carbon-carrier for effecting backward shift of the latter upon movement of the handle.

12. In a typewriting machine, a rotatable 95 platen, a carriage for the platen, a paper-table on the carriage, inclined upward and rearward at the rear of the platen, means for holding work-webs, having carbons interleaved therewith, for line-space feed with 100 the platen, a table inclined upward and rearward in a substantially straight-line continuation of the paper-table on the platen-carriage, and over which the composite web is fed toward the platen, a carbon-carrier on 105 the last-mentioned table, to which the carbons are connected at their rear, and means for shifting the carbon-carrier rearward on its table.

13. In a continuous billing typewriting 110 machine, the combination of a carriage, a cylindrical platen on said carriage around which continuous work-sheets with interleaved carbon-sheets may be fed, a table at the introductory side of the platen, a carbon-carrier to which the carbon-sheets are attached, said carbon-carrier being adapted to travel over said table toward and away from said platen, an operating handle on said table, and gear-actuated means connecting 115 said operating handle with said carbon-carrier to actuate the latter.

14. In a continuous billing typewriting machine, the combination of a carriage, a cylindrical platen on said carriage around which 120 continuous work-sheets with interleaved carbon-sheets may be fed, a carbon-carrier to which the carbon-sheets are attached, means on said carriage to support said carbon-carrier, said carbon-carrier being adapt- 125 130

ed to move toward and away from said platen, an operating handle pivoted on said carriage, gear-actuated means, and a belt connecting said operating handle with said 5 carbon-carrier to actuate the latter, the parts being so arranged that a forward throw of said handle moves the carbon-carrier away from the platen.

15. In a continuous billing typewriting 10 machine, the combination of a carriage, a cylindrical platen on said carriage around

which continuous work-sheets with inter-leaved carbon-sheets may be fed, a straight table on said carriage, said table extending tangentially from the platen, a carbon-carrier to which the carbon-sheets are attached, and gear-actuated means, means to actuate the carbon-carrier to move the work-sheets with the carbon-sheets to free the carbon-sheets from the platen.

JOHN WALDHEIM.
